[57] CLAIM

The ornamental design for a animal feeding bowl, as shown and described.

DESCRIPTION

FIG. 1 is a perspective view taken from the top and front of the animal feeding bowl, showing our new design;

FIG. 2 is a top plan view thereof;

FIG. 3 is a front elevation thereof; and,

FIG. 4 is a side elevation thereof.

The unshown sides are a mirror images of the sides shown in FIGS. 3 and 4.

FIG. 1

FIG. 2

FIG. 3

FIG. 4
